United States Patent Office

Des. 208,745
Patented Sept. 26, 1967

208,745

SKIN GRAFT CUTTER

Charles C. Hill, Ann Arbor, Mich., assignor to Michigan Research Corporation, Ann Arbor, Mich., a corporation of Michigan

Filed Dec. 29, 1966, Ser. No. 5,224

Term of patent 14 years

(Cl. D83—12)

FIG. 1

FIG. 2

FIG. 3

FIG. 4

FIG. 1 is a side elevational view of a skin graft cutter embodying my novel design.

FIG. 2 is an end view of the same.

FIG. 3 is a top plan view of the same.

FIG. 4 is a bottom plan view of the same.

I claim:

The ornamental design for a skin graft cutter, as shown and described.
